UNITED STATES PATENT OFFICE

154,245

DESIGN FOR A LAMP

John F. Davidson, Linden, N. J.

Application March 1, 1948, Serial No. 144,849

Term of patent 14 years

(Cl. D48—20)

To all whom it may concern:

Be it known that I, John F. Davidson, a citizen of the United States, residing at Linden, in the county of Union and State of New Jersey, have invented a new, original, and ornamental Design for a Lamp, of which the following is a specification, reference being had to the accompanying drawings, forming part thereof.

I claim:

The ornamental design for a lamp, as shown.

JOHN F. DAVIDSON.
